UNITED STATES PATENT OFFICE.

STATES LEE LEEBY, OF SAVANNAH, GEORGIA.

SUPPORTING BRACKET FOR SPOTLIGHTS AND THE LIKE.

Application filed March 26, 1921. Serial No. 455,749.

To all whom it may concern:

Be it known that I, STATES LEE LEEBY, a citizen of the United States, and a resident of Savannah, in the county of Chatham and 5 State of Georgia, have invented certain new and useful Improvements in Supporting Brackets for Spotlights and the like, of which the following is a specification.

My present invention relates to improvements in brackets for supporting articles from a fixed member, and is designed more especially with a view to attaching what are commonly known at "spot lights" to the windshields of automobiles, though not necessarily limited to this particular use.

Windshields of motor vehicles are sometimes arranged in a vertical plane and sometimes inclined, and one of the objects of the present invention is to provide a bracket by 20 which the lamp or projector may be applied to either a vertical or inclined windshield at will.

Another object is to provide a bracket by 25 which the spot light may be so attached to the windshield that while the light will have the range of movement necessary for road illumination, it will be impossible to elevate the beam sufficiently to dazzle approaching drivers.

30 The invention further aims to provide an extremely simple, efficient, economical and durable construction, and with these and other objects in view, the invention includes the novel features of construction and arrangement and combination of parts hereinafter described and particularly defined by the appended claims.

An embodiment of my invention is illustrated in the accompanying drawings in 40 which:

Figure 1 is a view of the device in elevation;

Fig. 2 is a plan view;

Fig. 3 is an end view; and

45 Fig. 4 is a detail.

Referring by reference characters to these drawings, the numeral 1 designates the body of the bracket or bracket arm, one end or portion of which is designed to be secured to the windshield frame or standard and the other end to carry the spot light. I have shown this bracket arm as constructed to 50 adjustably and detachably support a spot light after the manner disclosed in an application filed by me in the United States

Patent Office on the 7th day of February, 1921, Serial Number 443,196, the arm 1 having a concavo-convex portion 1^a, the concavity of which fits the curved back wall of the lamp against which it is frictionally held by a clamping plate, the lamp having a spindle which projects through the central opening *a* of the said concavo-convex portion, and the slot *a'* being provided to enable the lamp to be removed from its support. The bracket arm is provided with a portion 1^b at one end which is designed to form the one part of a clamp, and I prefer to form the entire arm including the lamp engaging portion and the clamp member 70 or portion in one piece from sheet metal which may be conveniently stamped or die cut into the proper shape. The said end portion 1^b is preferably formed by bending the metal at right angles to form or provide two portions *b* and *b'* connected at the end by a transverse web *b*² for strengthening purposes and also to assist in forming the seat for the abutment member hereinafter described. The other portion of the clamp 75 or clamping member comprises a bracket iron 2 having a foot 2^a which is secured in any suitable manner to the member, conveniently by means of a screw or rivet, and it has an angularly turned outer end 2^b designed to overlie the opposite side of the windshield frame or standard when the bracket has been placed with the clamping portion of the bracket against one side of such frame member or standard. 80

The side edges of the bracket arm are preferably turned over at substantially a right angle as indicated at 1^x to impart additional strength and rigidly to the intermediate portion of the arm, and these overturned 85 portions are cut away as indicated at *x* which provides two seats to receive an abutment member 3. This is in the form of a bar or member having a substantially arc-shaped rear face adapted to be movably held 90 in the seat formed by the recesses or cut away portions *x* and the intermediate angular pocket formed by the angular bent portions of the bracket. On its opposite side or face the bar or member 3 is designed to 95 abut against the windshield standard, and I prefer to have it abut at two points, as this, in connection with the clamping device carried by the bracket iron 2, gives me a three point bearing. This is preferably ac- 100 105 110

complished by making the member 3 in the shape of a substantially arc shaped bar and notching the ends as indicated at 3^a.

The angularly turned end of the bracket iron 2 carries a clamping device which may be in the shape of a screw 4 threaded through the bracket iron and arranged to bear against the windshield frame at a point intermediate the notched ends 3^a of the abutment member, thus giving the three point bearing above referred to.

Given a construction such as above described it will be readily seen that it may be instantly adjusted to fit a vertical or inclined windshield, as all that it is necessary to do is to slide the arc-shaped abutment member in relation to its seat and the inclination of the lamp relative to its support will be determined by the relative position of the ends of the arc-shaped abutment member against which ends the support will be clamped by the set screw.

It will also be readily understood that by this means, in applying the lamp to the windshield it may be so adjusted that the

lamp may not be raised, during its normal adjustments, beyond the limits allowed by law.

Having thus described my invention, what I claim is:

1. The combination with a supporting bar of, a bracket having a seat, an arcuate abutment member having its convex face slidably supported by said seat and its ends abutting one face of said bar, and an opposed clamping member carried by said bracket and engaging the opposite face of said bar intermediate the ends of said arcuate member.

2. In combination, a bracket arm of sheet metal, having a lamp supporting portion and an angular portion provided with seats in the edges thereof, an arc shaped bar slidably supported by said seats, a bracket iron secured to said arm and having a part overlying said arc-shaped bar, and a clamping screw threaded through said overlying part.

In testimony whereof, I affix my signature.

STATE S. LEE LEBBY.
